Application June 1, 1932, Serial No. 614,686

14 Claims. Cl. 103—5

This invention relates to a mechanism for raising or elevating liquids. The invention is herein illustrated as applied to the raising of water in a relatively deep well, but it may be used in other instances where the body of liquid and the point of delivery of the liquid are at different levels, that is, where the vertical distance between such levels is greater than the highest height of a column of the liquid that the pressure of the atmosphere will sustain.

In practice, in connection with the raising of water, it has been generally recognized that suction pumps may be used where the surface of the water in the well below the pump piston, measured vertically, does not exceed approximately twenty-five feet. Where the well is of greater depth, equipment known as deep well apparatus must be used, such equipment usually including a working barrel and a power head, and increasing materially the cost of installation and up-keep; also, the power head must be mounted directly over the well casing.

We have provided mechanism which, in connection with a suction pump such as ordinarily employed for raising water from shallow wells, that is, where the surface of the water is less than 25 feet below the suction pump cylinder, is capable of raising water from depths heretofore requiring deep well apparatus of the above type or other forms of construction, thereby providing for a simpler and cheaper installation.

One object of our invention is to provide an improved mechanism intermediate the well and a pump of the suction type capable of raising or pumping liquid, for example, water, from great depths.

Another object of the invention is to provide in the riser leading from a well, mechanism co-operable with the suction effect of a suction pump to raise water from relatively great depths.

A further object of the invention is to combine with a suction pump, improved means for elevating water or other liquids.

A still further object of the invention is to provide an improved liquid raising mechanism of simple construction and capable of being readily and economically installed.

Other objects of the invention will be apparent to those skilled in the art to which our invention relates from the following description taken in connection with the accompanying drawings, wherein

Fig. 1 is an elevation of an apparatus, embodying our invention, such apparatus being shown mounted or installed in a well,

Fig. 2 is a fragmentary sectional view, showing the control member in its raised position.

Fig. 3 is a view similar to Fig. 2, but showing the control member in its lower position.

Fig. 4 is a section on the line 4—4 of Fig. 2. 5

Fig. 5 is a section on the line 5—5 of Fig. 4.

Fig. 6 is a section on the line 6—6 of Fig. 2.

Fig. 7 is a fragmentary view of the lower end of the riser, with parts broken away.

Figs. 8 and 9 are views substantially similar to 10 Figs. 2 and 3, respectively, but showing a different embodiment of the invention.

Fig. 10 is a section on the line 10—10 of Fig. 9.

Fig. 11 is a section on the line 11—11 of Fig. 8.

Fig. 12 is a section on the line 12—12 of Fig. 9. 15

In the drawings, 1 indicates a well and 2 indicates the body of water therein. 3 indicates a suction pump, preferably power driven. The pump 3 may be of any desired construction and provided with single or double acting cylinders, 20 one being indicated at 4 and provided with a vacuum chamber or suction intake 5, in which a suction effect is constantly maintained by the pump so long as it is operated. The pistons are suitably operated by means of eccentrics on the shaft 6, 25 carrying a pulley 7, the latter being belted to a pulley 8, which is driven by the motor 9. The pump 3 rests on a base 10 which may be at any desired location; directly over or remote from the well opening, as desired. The arrangement herein shown is such that the surface of the water 2 is more than 25 feet but less than 50 feet below the pump pistons. When the well is at this depth, we provide what may be termed a single stage 30 raising mechanism, indicated as an entirety at 11; where the distance is more than 50 feet but less than 75 feet, a second raising mechanism 11 would be required; one such mechanism being required for approximately each twenty-five of depth.

12 indicates a main riser leading from a point 40 below the surface of the water 2 upwardly into a casing 13 serving as a filling and emptying reservoir and forming part of the liquid raising mechanism 11. The lower end of the riser 12 is provided with a foot-valve 12a, preferably comprising a 45 plate pivoted within the riser to swing upwardly (see dotted lines in Fig. 7) and held against movement downwardly by a shoulder 12b. The purpose of the foot-valve 12a is to hold or support water drawn into the riser 12 from flowing back into 50 the well 1; when the suction effect in the riser 12 or other parts connected thereto, is released or broken, as later set forth. 14 indicates a supplemental riser leading from a point within and adjacent the lower portion of the casing 13 to the 55

intake 5. The casing 13 is preferably of cylindrical shape and consists of a sheet metal side wall provided with lower and upper heads 15, 16, respectively. The heads 15, 16, are preferably 5 threaded into the ends of the casing 13 and form a closed, substantially sealed chamber for reasons which will later appear. The upper end of the riser 12 is threaded into an opening formed in the head 15. The riser 14 is preferably of sectional 10 construction to facilitate assembly, the section within the casing being threaded at its end portion through an opening formed in the head 16 and connected by a union or coupling 17 to the other section of the riser 14.

15 18 indicates a conduit leading through the casing 13 and having a branch 18a connected to the supplemental riser 14. 19 indicates a valve for controlling the flow of air through the conduit 18 into the casing 13 and flow of air or water through 20 conduit 18 and branch 18a from the casing 13 into the riser 14, as later set forth. The conduit 18, branch 18a and valve 19 preferably comprise the following parts: 20 indicates a pipe or tube extending through an opening formed in the casing 25 head 16 and provided on its outer end with a collar 21 preferably of hexagon shape to take a tool. The inner end of the tube is provided with screw threads and threaded into the casing 22 for the valve 19. The tube 20 is of such length that when 30 it is screwed into the valve casing 22, the latter and collar are clamped against the opposite faces of the head 16 to seal the opening therethrough. When desired, gaskets (not shown) may be positioned between the collar 21 and valve casing and 35 the head. The pipe or tube 20 and the passage through the valve casing 22 constitutes the conduit 18. The valve casing 20 is provided with a hollow lateral portion 24 threaded into an opening 23 formed in the riser 14 within the casing 13, 40 the passage through such lateral portion 24 constituting the branch conduit 18a leading from the conduit 18 to the riser 14. The valve element 25 for the valve 19 is formed with three connected 45 passages, so that in one position of the valve element, as shown in full lines in Figs. 2 and 5, the conduit 18 is closed from the exterior but connected by branch 18a to the riser 14, so that air or water may flow from the casing 13 into the riser 14 and in the other position of the valve element, 50 as shown in full lines in Fig. 3 and dotted lines in Fig. 5, the branch 18a is closed and the conduit 18 is open to provide an inlet for air from the exterior of the casing 13 thereinto for a purpose later to appear.

55 26 indicates a member for controlling the operation of the valve 19. In the form of construction in Figs. 1 to 6, inclusive, the member 26 consists of a receptacle, open at its upper end to receive the lower end of the riser 14, and slidably vertically in the casing 13. The receptacle 26 is preferably guided in its up and down movements and connected to the valve element 25 by linkage indicated as an entirety at 27. The guide means for the receptacle 26 may comprise a plurality of 60 arms 28 suitably fixed to the bottom of the receptacle and extending radially relative to the side wall thereof (see Figs. 2, 3 and 6); also, these arms 28 may be bent downwardly, as shown at 65 28a, forming stops to limit the downward movement of the receptacle 26 at a point spaced from the head 15. The linkage 27 consists of the following: 29 indicates a lever fixed to the valve element 25. 30 indicates a rod pivotally and slidably connected at its upper end to the lever 29 and 70 operatively connected to the receptacle 26, so that

the rise and fall of the latter will actuate the lever 29 to move the valve element from one position to its other position in either direction. Due to the fact that the distance of travel of the receptacle 26 is greater than the swinging movement of the lever 29, the operative connection between the rod 30 and the receptacle 26 permits the latter to move relative to the rod 30 before operating it. To provide for this operation, the receptacle 26 carries on one side wall a vertical strip 31 (the strip being preferably riveted to the side wall) having inturned end portions 32, 32a, in which are formed aligned openings to slidably receive the rod 30 and guide it during relative movement between the rod and the receptacle. The rod 30 is provided with laterally extending pins or tappets 33, 33a, above and below the guide portions 32, 32a, respectively and spaced with respect to each other so that the receptacle may move in either direction the required amount in excess of that necessary to swing the lever 29. In the upward movement of the receptacle, the guide portion 32 engages the pin 33 and through it moves the rod 30 upwardly, such movement being limited by the engagement of the rod 30 with the head 16 (see Fig. 2); in the downward movement of the receptacle, the guide portion 32a engages the pin 33a and through it moves the rod 30 downwardly, such movement being limited by the engagement of the stops 28a with the head 15 (see Fig. 3).

30 Operation: When our mechanism is first installed, it is primed by first closing the conduit 18 and starting the pump 3 to create sufficient vacuum in the system to cause the water to rise and fill the riser 12 and casing 13 up to approximately 35 the level shown in Fig. 2. When the rising water enters the casing 13 as just stated, the receptacle 26 is raised thereby to its uppermost position and the valve 19 closes the conduit 18 to the outside atmosphere, but connects it through the branch 40 conduit 18a with the riser 14. The pump 3 may be continued in operation. If stopped it may be restarted. By reason of such operation, the remaining air in the system will be exhausted to create a vacuum in the casing 13 and riser 14, the effect 45 of which will be to raise water (due to pressure of the atmosphere on the surface of the water 2) through the riser 12 into the casing 13 and cause it to overflow into and fill the receptacle 26. When the weight of the water in the receptacle 26 exceeds that displaced by the latter, it will move downwardly to the position shown in Fig. 3, and through the linkage 27 move the valve element 25 to the position shown in this view (also shown 50 in dotted lines in Fig. 5), whereupon air will be admitted to the casing 13 through conduit 18. The admitted air will break the vacuum in the casing and permit the suction effect of the cylinders 4, due to atmosphere pressure on the surface 55 of the water in the casing 13, to raise the water in receptacle 26 and excess water in the casing 13, through the riser 14 to the intake 5 and cylinders 4 from which it is discharged into a reservoir or receiver (not shown). As the water in the receptacle 26 is withdrawn, it gradually rises to its first 60 position (Fig. 2) and operates the valve 25 to its initial position, thereby closing the conduit 18 to the outside atmosphere and sealing the casing 13. When the conduit 18 is opened to admit air into the casing 13, the water then filling the riser 12 and casing 13 is held against gravitation into the well 1 by the foot-valve 12a.

65 As soon as the conduit 18 is closed and any free air remaining the casing 13 and riser 14 is exhausted therefrom, water will again rise in the 70 75

riser 12 and casing 13 and overflow into the receptacle 26 which will then gravitate downwardly and operate the valve 19 to open the conduit. This cycle of operation will continue so long as the 5 pump 3 is operated.

The branch conduit 18a provides for the suction effect of the cylinders 4 upon the surface of the water when and after the latter overflows into the receptacle 26 and closes off the lower end 10 of the riser 14.

While the receptacle 26 gradually gravitates when being filled and gradually rises when being emptied, it will be noted that it does not operate the valve lever 29 until it traverses the last portion 15 of its movement in either direction. This manner of operation results from the provision between the receptacle 26 and lever 29 of a lost-motion connection which has already been described.

20 Figs. 8 to 12, inclusive, illustrate a different embodiment of our invention in which the control member is in the form of a float, indicated at 26'. The float in cross section corresponds in shape to the casing 13 and its end walls support 25 a tubular member 34 loosely fitting the riser 14 within the casing 13 to guide the float upwardly and downwardly therein. At one side of the tubular member 34, the end walls of the float 26' support a tubular member 35 through which extends the rod 30, the latter forming one element of the operative connection 27' between the float 26' and the valve element of the valve 19'. The rod 30 is provided with laterally extending pins or tappets 33', 33a' with one of which the float 35 engages when moving in either direction. The pins or tappets 33', 33a', are so spaced that the float 26' only engages therewith as it nears the end of its movement in either direction.

By reason of the fact that in this embodiment 40 of the invention, a float is used instead of a receptacle that is filled and emptied, the conduit 18 is closed to the outside atmosphere but open through the branch conduit 18a when the lever 29 is moved downwardly (Fig. 8), whereas the 45 branch conduit 18a is closed and the conduit 18 open to admit air to the casing 13 when the lever 29 is moved to the position shown in Fig. 9.

Fig. 8 shows the position of the float 26' when the casing 13 is substantially empty, with the conduit 18 closed. If the pump 3 is started, air in the riser 14 and casing 13 will be exhausted through the branch conduit 18a to create a vacuum therein, whereupon water will rise from the well 1 through riser 12 and casing 13. The water rising in the casing 13 will elevate the float 26', which through its engagement with the pin 33' will lift the rod 30 and swing the lever 29 to the position shown in Fig. 9. This operation 50 opens the conduit 18 to admit air into the casing 13 above the water level therein, thereby breaking the suction effect and permitting the cylinders 4 of the pump 3 to raise the water in the casing 13 through the rise 14, the water in the riser 12 being held therein by the foot valve 12a already referred to. As the water is withdrawn 60 from the casing 13, the float 26' gravitates downwardly and by engagement with tappet 33a' operates the valve 19' to its first position. The cycle of operations will then be repeated and continue 65 so long as the pump 3 is continued in operation.

The upward movement of the lever 29, rod 30 and float 26' is preferably limited by the engagement of the rod 30 with the head 16. The downward movement of these parts is preferably 70 limited by the engagement of the lever 29 with an

arm 36 carried by the valve 19'. The inner end of the arm 36 terminates in a clip whereby it may be removably and adjustably connected to the valve 19'. The free end of the arm is provided with an extension 37 having an offset portion forming locking shoulders 38 one of which is engaged by the lever 29 in either position. As the arm 36 is formed of resilient material, the shoulders 38 form yieldable locks to maintain the lever in either position against frictional engagement between the tube 35 and rod 30, but permits the lever 29 to operate when the float 26' engages one of the tappets.

It will be noted that in our forms of construction, but one pipe, conduit or riser leads upwardly from the body of water in the well and but one pipe, conduit or riser extends from the pump 10 downwardly into the well 1. Also, that the raising mechanism 11 is connected to these risers, so that the entire apparatus may be assembled 15 and installed in an easy manner.

It will also be noted that in the event the well 20 becomes flooded, that is, the level of the water 2 rises above the casing 13, the operation of the pump 3 and raising of water from the well is not 25 affected, since under such conditions the control receptacle 26 in the first described embodiment will be in its lower position and the control float 26' in the second described embodiment will be in its uppermost position. Accordingly, the conduit 30 30 from the outside to the inside of the casing 13 will be open, so that the suction effect of the pump cylinders will cause the water in the well to flow through the conduit 18, into the casing 13 and from the latter through riser 14 until the water 35 level drops below the inlet to the conduit. Thereafter, the mechanism 11 will operate as herein set forth.

In practice, the distance from the water level 40 in casing 13 when filled to its normal level to the cylinders 4 should not exceed approximately 25 feet and the distance from the top of the receptacle 26 (or lower end of riser 14 in the Fig. 8 form of construction) to the level of the water 2 in the well 1 should not exceed approximately 25 feet but this distance may in each case be increased where a high or relatively perfect vacuum 45 can be maintained in the system.

To those skilled in the art to which our invention relates, many changes in construction and 50 widely differing embodiments and applications of the invention will suggest themselves without departing from the spirit and scope thereof. Our disclosures and the description herein are purely 55 illustrative and are not intended to be in any sense limiting.

What we claim is:

1. In a liquid raising apparatus, the combination with a suction pump having an intake, of a liquid conduit connected to said intake and leading 60 downwardly, the lower end of said conduit being adapted to be disposed below the level of a body of the liquid to be raised, said conduit including a casing intermediate the ends thereof, a valve on the lower end portion of said conduit, an air inlet 65 provided in the upper portion of said casing, a valve in said inlet, a receptacle movably mounted in said casing and arranged to receive the lower end of that portion of the conduit extending upwardly from said casing, said receptacle being arranged to be elevated by the rise of the liquid drawn into said casing and to be lowered by the weight of the liquid overflowing thereinto, and operating connections between said receptacle and 70 said last mentioned valve arranged to close said 75

valve when said receptacle moves upwardly and to open said valve when it moves downwardly.

2. In a liquid raising apparatus, the combination with a suction pump having an intake, of a liquid conduit connected to said intake and leading downwardly, the lower end of said conduit being adapted to be disposed below the level of the body of the liquid to be raised, said conduit including a casing intermediate the ends thereof, a valve on the lower end portion of said conduit, an air inlet provided in the upper portion of said casing, a valve in said inlet, a receptacle movably mounted in said casing and arranged to receive the lower end of that portion of the conduit extending upwardly from said casing, said receptacle being arranged to be elevated by the rise of the liquid drawn into said casing and to be lowered by the weight of the liquid overflowing thereinto, operating connections between said receptacle and said last mentioned valve arranged to close said valve when said receptacle moves upwardly and to open said valve when it moves downwardly, and means for limiting the movement of said receptacle.

25 3. In a liquid raising apparatus, the combination with a suction pump having an intake, of a liquid conduit connected to said intake and leading downwardly, the lower end of said conduit being adapted to be disposed below the level of a body of the liquid to be raised, said conduit including a casing intermediate the ends thereof, a valve on the lower end portion of said conduit, an air inlet provided in the upper portion of said casing, and having connection with said conduit, a valve arranged in one position to close said inlet and connect said casing to said conduit and in another position to close said connection to said conduit and open said inlet, and means in said casing and controlled by the flow of water into and out of said casing for operating said last mentioned valve.

40 4. In a liquid raising apparatus, the combination with a suction pump having an intake, of a sectional riser having its upper section connected to said intake and extending downwardly, the lower end of the lower section of the riser adapted to be disposed below the level of a body of liquid and provided with a valve free to operate when the liquid flows into said riser section, a normally closed casing into which the adjoining ends of the riser sections extend, valve mechanism in the upper portion of said casing arranged to admit air thereinto or permit air flow from said casing into said upper riser section, and means in said casing controlled by the flow of liquid thereinto for actuating the valve of said valve mechanism.

45 5. In a liquid raising apparatus, the combination with a suction pump having an intake, of a sectional riser having its upper section connected to said intake and extending downwardly, the lower end of the lower section of the riser adapted to be disposed below the level of a body of liquid and provided with a valve free to operate when the liquid flows into said riser section, a normally closed casing into which the adjoining ends of the riser sections extend, a valve mechanism for admitting air into said casing or permitting air to flow from said casing into said upper riser section, and a float mechanism in said casing, actuated by the rise and fall of liquid therein and operatively connected to said valve mechanism for controlling the operation thereof.

70 6. In a liquid raising apparatus, the combination with a suction pump having an intake, of a sectional suction and liquid conduit having its upper end connected to said intake and extending

downwardly, said conduit comprising an upper section, a lower section and an intermediate section connected one to the other in series, the lower end of the lower section of the conduit being adapted to be disposed below the level of a body of liquid and provided with a valve free to operate when the liquid flows into said section and said intermediate section consisting of a casing, a valve mechanism for admitting air into said casing or connecting said casing to said upper section, means for yieldingly holding the valve element of said valve in opened or closed position, and a member movable in said casing and operatively connected to the valve element of said valve for operating it from one position to its other position.

7. In a liquid raising apparatus, the combination with a suction pump having an intake, of a sectional riser having its upper section connected to said intake and extending downwardly, the lower end of the lower section of the riser adapted to be disposed below the level of a body of liquid and provided with a valve free to operate when the liquid flows into said riser section, a closed casing connected at its lower end to the upper end of said lower riser section, the upper riser section extending into said casing to a point near its bottom and open at its lower end, an air inlet leading into the upper portion of said casing, an air inlet leading from the upper portion of said casing into the upper riser section, and means within said casing and controlled by the rise and fall of liquids therein for controlling the flow of air through said inlets.

20 8. In a liquid raising apparatus, the combination with a suction pump having an intake, of a sectional riser having its upper section connected to said intake and extending downwardly, the lower end of the lower section of the riser adapted to be disposed below the level of a body of liquid and provided with a valve free to operate when the liquid flows into said riser section, a normally closed casing into which the adjoining ends of the riser sections extend, and means for controlling the admission of air into said casing or from said casing into said upper riser section, said means including a member movable in said casing and arranged to be operated by the flow of the liquid into and out of said casing.

25 9. In a system for raising liquids having a suction creating means, a sectional riser extending downwardly into the liquid to be raised and comprising a section connected to said suction creating means; a lower section and an intermediate casing in which the adjacent ends of said sections open, which consists in continually operating said suction means to maintain suction effect in said riser, closing said casing and connecting it to said first mentioned section to effect flow of the liquid through said lower riser section into said casing to substantially fill it and then disconnecting said casing from said first mentioned section and admitting air to the surface of the liquid in said casing to induce a flow of the liquid therein upwardly through said upper riser section to its exit.

30 10. In apparatus for raising liquid, the combination of a riser having its lower end extending into the body of liquid to be raised, a valve on the lower end portion of said riser arranged to permit the liquid to flow into said riser, a casing connected to the upper end of said riser arranged above the body of liquid a distance less than the height of a column of the liquid that the pressure of the atmosphere will sustain, a

- riser having its lower inlet end open and connected to the lower portion of said casing, a suction pump having an intake connected to the upper end of said last mentioned riser, an air inlet disposed in the upper portion of said casing, an air connection from said casing to said last mentioned riser, and means in said casing and controlled by the rise and fall of liquid therein for controlling the supply of air into said casing or from said casing into said last mentioned riser.
11. In apparatus for raising liquid, the combination of a riser having its lower end extending into the body of liquid to be raised, a valve on the lower end portion of said riser arranged to permit the liquid to flow into said riser, a casing connected to the upper end of said riser arranged above the body of liquid a distance less than the height of a column of the liquid that the pressure of the atmosphere will sustain, a riser extending into said casing and having an open end terminating adjacent the bottom of said casing, an air inlet disposed in the upper portion of said casing and having a passage connected to said last mentioned riser, a valve in said inlet to control the flow of air into said casing or from said casing into said last mentioned riser, and a movable member in said casing operated by the rise and fall of the liquid therein and operatively connected to said last mentioned valve for operating it.
12. In apparatus for raising liquids in a well below the normal range, the combination with a well tube, of a single conduit extending downwardly into said tube to a point below the level of the body of liquid therein, said conduit comprising upper and lower sections and a reservoir intermediate said sections into which the upper section terminates an air inlet from the upper portion of said reservoir into said upper conduit section, the terminating end of said upper section being open, a liquid suction pump connected to the upper end of said upper conduit section for applying suction to lift liquid into said reservoir, and means in said reservoir arranged to close said air connection and admit air at atmospheric pressure into said reservoir for diverting the suction effect of the pump upon the body of liquid to the liquid in said reservoir to lift the liquid therefrom.
13. In a liquid raising apparatus, the combination with a suction pump having an intake, of a combined suction and liquid conduit connected at its upper end to said intake, said conduit comprising an upper section, a lower section and an intermediate section, and means in said intermediate section and controlled by the rise of liquid therein to admit air at atmospheric pressure therein or to connect the upper end of said section to said upper section, whereby the suction effect of said pump through said conduit is operable to first raise liquid through said lower section to said intermediate section and to then raise the liquid in said intermediate section through said upper section.
14. In a liquid raising apparatus, the combination with a suction pump having an intake, of a combined suction and liquid conduit connected at its upper end to said intake, said conduit comprising an upper section, a lower section and an intermediate section, and means in said intermediate section and controlled by the rise of liquid therein to admit air at atmospheric pressure therein or to connect the upper end of said section to said upper section, whereby the suction effect of said pump through said conduit is operable to first raise liquid through said lower section to said intermediate section and to then raise the liquid in said intermediate section through said upper section, said means comprising an air controlling valve and a float for operating said valve.

HAROLD B. COCHRANE.
ULRICH SPRINCHORN. 40
